United States Patent Office

Des. 188,005
Patented May 24, 1960

188,005

PLY WRENCH

Leonard C. Osborn, Salt Lake City, Utah, assignor to
Gardner Machines, Incorporated, Salt Lake City, Utah,
a corporation of Utah

Filed Dec. 31, 1958, Ser. No. 54,010

Term of patent 14 years

(Cl. D54—16)

Figure 1 is a side elevational view of a ply wrench, showing my new design;
Figure 2 is a top plan view of the ply wrench;
Figure 3 is a front elevation; and
Figure 4 is a rear elevation.
The dominant features of my design reside in the portions shown in full lines.

I claim:
The ornamental design for a ply wrench, substantially as shown and described.
